UNITED STATES PATENT OFFICE

CHARLES O. SMITH, OF SEBRING, OHIO, ASSIGNOR OF ONE-HALF TO THE SEBRING POTTERY COMPANY, OF SEBRING, OHIO, A CORPORATION OF OHIO, AND ONE-HALF TO THE LIMOGES CHINA COMPANY, OF SEBRING, OHIO, A CORPORATION OF OHIO

PROCESS OF EDGE DECORATION

Application filed November 26, 1930. Serial No. 496,354.

The invention relates to the edge decoration of plates, dishes and other articles of table earthenware, and more particularly to a process for under the glaze edge decoration of such articles, by which a feather edge or ripple edge decoration is applied.

The method, now in general use in potteries throughout the country, for applying an under the glaze edge decoration to such articles requires the services of highly skilled workers who have to serve an apprenticeship of three years before they become sufficiently expert in their work to produce a salable article.

15 This ordinary method of edge treatment is accomplished by applying a line of uniform thickness around the edge of the plate, or other articles to be decorated, by means of a camel's hair brush dipped in color mixed with oil.

It is then necessary for the plate, or other articles so decorated, to be fired in what is known as a "hardening on" kiln, in order to drive out the oil and cause the color to 25 adhere to the earthenware. If the color were not subjected to this "hardening on" fire, it would not be possible to properly glaze the ware by dipping it in the usual manner, as the glaze would not cover the 30 color, and also the color would be so easily removed by contact that it would be entirely too fragile for practical purposes.

After this "hardening on" fire, the plate, or other article, is then glazed by dipping, 35 after which it is again placed in a kiln and fired to harden the glaze. Thus it is seen that in the usual method of applying edge decorations to table earthenware, skilled workers are required and two fires of each 40 article are necessary. It is impossible to apply the edge decoration by the usual method without the "hardening on" fire, as the continuity of the edge line would be broken by contact with the worker's thumb 45 or fingers if the article were dipped before the "hardening on" fire, and furthermore, as above described, the glaze would not cover the color in the edge decoration unless the same had been fired.

50 Another method of applying edge decora-

tions under the glaze, which is used to some extent, is the printing process in which a copper plate engraving is made of the edge decoration and the same is applied by hand to the article. In this method, as well as 55 the ordinary and usual method above described, it is necessary for the color to be hardened on by a "hardening on" fire, before the article may be glazed by dipping.

The object of the present improvement 60 is to provide a novel process by means of which edge decorations may be applied to table earthenware by unskilled workers with only a single firing of the article, thus materially reducing the cost of decorating 65 the edges of such ware.

The above, and other objects which will be apparent as the description continues, may be attained by applying a ripple edge or feather edge decoration to the ware, using 70 a water color which does not require a "hardening on" fire before dipping.

This ripple or feather edge decoration does not require the services of a skilled worker and may be easily and quickly applied to the ware by any desired one of several methods.

A preferred method of applying this edge decoration is by the use of a camel's hair brush dipped in the water color, the strokes 80 of the brush being made across the edge of the plate or toward the center thereof, producing an edge decoration of more or less irregular shape. No "hardening on" fire is required to harden this water color decoration before dipping, and it has been found that the contact of the worker's thumb or fingers with this irregular edge decoration in dipping the ware does not noticeably mar the decoration.

85 This edge decoration may also be applied by means of a so-called "silk sponge" using water color such as above referred to and producing a more or less irregular border or edge decoration upon the ware.

90 Another method of carrying out the invention is by means of a stencil having the ripple or feather edge design cut therein, this stencil being placed over the plate and water color, such as above referred to, 11

sprayed or otherwise applied to the edge of the plate.

In the accompanying drawings, Figure 1 is a plan view of a portion of a plate to which the new edge decoration has been applied as by a brush;

Fig. 2, a similar view showing the edge decoration as applied by a stencil; and

Fig. 3, a similar view showing the effect 10 of edge decoration produced by a "silk sponge."

Similar numerals refer to similar parts throughout the drawings.

Although in the drawings the invention is 15 illustrated as applied to round plates, it should be understood that this is only for the purpose of illustration and the invention is equally applicable to the edge decoration of square, oblong or other shapes of 20 plates or, in fact, any earthenware table articles.

In carrying out the process to produce the edge decoration shown in Fig. 1 of the drawings, the edge portion 10 of an unglazed 25 plate or other earthenware table article indicated generally at 11 may have the edge decoration, shown at 12, applied thereto by means of a camel's hair brush, using a color combined with water, the strokes of the 30 brush being across the edge of the plate radially toward the center thereof, producing a more or less irregular decoration, as shown on the drawings.

This water color used for the edge decoration 35 does not require a "hardening on" fire before dipping and is easily covered by the glaze. This permits the unglazed article with the edge thus decorated to be dipped and then fired, completing the decoration of 40 the plate in a single fire as compared with the two fires necessary under the method now in general use.

If desired, the decoration may be applied 45 by using a stencil with the ripple or feather edge design therein, this stencil being placed over the plate and water color, as above referred to, being sprayed thereon, producing an edge decoration such as illustrated at 13 in Fig. 2.

50 As shown in Fig. 3, the edge decoration indicated at 14 may be applied by means of a small "silk sponge" using the water color above referred to. The processes indicated in Figs. 2 and 3 are otherwise carried out in 55 the same manner as above described regarding Fig. 1.

From the above it will be seen that the improved process for edge decoration of earthenware materially reduces the cost of such 60 edge decoration as the decorating may be done by unskilled workers and the "hardening on" fire, necessary under present practice, is eliminated.

I claim:

55 1. The under glaze process of edge deco-

rating table earthenware which consists in applying a ripple or feather edge water color decoration to the edge portion of a piece of unglazed earthenware, then dipping the decorated earthenware before firing, to 70 glaze the same, and then firing the glazed earthenware.

2. The under glaze process of edge decorating table earthenware which consists in applying a ripple or feather edge water 75 color decoration to the edge portion of a piece of unglazed earthenware by means of a brush stroked across the edge of the earthenware, then dipping the decorated earthenware before firing, to glaze the same, and 80 then firing the glazed earthenware.

3. The under glaze process of edge decorating table earthenware which consists in applying a ripple or feather edge water color decoration to the edge portion of a 85 piece of unglazed earthenware by means of a silk sponge, then dipping the decorated earthenware before firing, to glaze the same, and then firing the glazed earthenware.

4. The under glaze process of edge decorating table earthenware which consists in applying a ripple or feather edge water color decoration to the edge portion of a piece of unglazed earthenware by means of a stencil, then dipping the decorated earthenware before firing, to glaze the same, and then firing the glazed earthenware. 95

In testimony that I claim the above, I have hereunto subscribed my name.
